(74) Attorney, Agent, or Firm — Russell Swerdon; Desmund Gean

(57) **CLAIM**

The ornamental design for a button set for an electronic device, substantially as shown and described.

DESCRIPTION

FIG. 1 is a front top left side perspective view of a button set for an electronic device showing our new design; and, FIG. 2 is a front view thereof.

The broken lines show environmental/illustrative purposes only and form no part of the claimed design.

1 Claim, 2 Drawing Sheets
